(57) **CLAIM**

The ornamental design for the razor cartridge, as shown and
described.

DESCRIPTION

FIG. 1 is a top front perspective view of the razor cartridge.

FIG. 2 is a bottom perspective view of the razor cartridge.

FIG. 3 is a top rear perspective view of the razor cartridge.

FIG. 4 is a top view of the razor cartridge.

FIG. 5 is a front view of FIG. 4.

FIG. 6 is an underside view of the razor cartridge.

FIG. 7 is a rear view of FIG. 4.

FIG. 8 is a left view of FIG. 4; and,

FIG. 9 is a right view of FIG. 4.

The broken lines shown in the drawings illustrate portions of
the razor cartridge and form no part of the claimed design.
